UNITED STATES PATENT OFFICE.

CHARLES P. FREESTATE, OF RIVERSIDE, ILLINOIS, ASSIGNOR TO WESTERN SHADE CLOTH COMPANY, OF CHICAGO, ILLINOIS, A CORPORATION OF ILLINOIS.

SHADE-ROLLER MOUNTING.

Application filed February 21, 1927. Serial No. 169,726.

The principal object of this invention is to provide an improved shade roller mounting in which the roller is held against endwise movement between the supporting brackets by a resiliently yieldable connection between one of the brackets and a cooperating trunnion on the roller.

Other objects and advantages of the invention will be evident to those skilled in the art upon a full understanding of the construction, arrangement and operation of the improved mounting.

One form of the invention is presented herein for the purpose of exemplification, but it will of course be appreciated that the invention is susceptible of embodiment in other structurally modified forms coming equally within the comprehensive scope of the appended claims.

20 In the accompanying drawing:

Fig. 1 is a side view of a shade roller which is rotatably supported in brackets and is provided at one end with the improved mounting for preventing end play.

25 Fig. 2 is a section, taken on the line 2—2 of Fig. 1;

Fig. 3 is a section, taken on the line 3—3 of Fig. 2; and

30 Fig. 4 is a section, taken on the line 4—4 of Fig. 3.

The roller and bracket assembly illustrated in the drawing is of the type commonly used in closed automobiles, but the improved mounting feature which forms the subject matter of this invention is of course applicable to roller and bracket assemblies of many other different types.

35 It will be observed that the roller 10 is supported by two brackets 11 and 12 which are secured by screws 13 to the upper corners of a window frame 14.

40 One end of the roller—the one containing the spring-winding mechanism—has projecting axially therefrom the flattened end 15 of the rod to which the spring is secured and on which the roller is journaled. The flattened end of the rod extends into a slot of corresponding cross section in the bracket 11, and is held against rotation by the same. 45 The construction thus far described is one which is commonly employed.

The other end of the roller has projecting

therefrom a trunnion 16 which extends through a circular bearing aperture 17 in the bracket 12 and has a cylindrical portion 18 55 journaled in such bearing. The trunnion has a groove 19 therein just beyond the portion 18, and the groove is occupied at opposite sides by two parallel portions 20 of a U-shaped wire spring 21 positioned against 60 the inside face of the bracket.

The spring is held in position by two inwardly punched loops 22 in the bracket, beneath which the extremities of the spring are inserted, and the spring is prevented from 65 working out from beneath either of the loops by the confining sides of a cap 23 which is secured against the inside face of the bracket about the periphery of the same. The cap 23 may be secured in position by tongues 24 70 which pass through slots in the bracket and are bent over against the outside face of the same. The end of the trunnion is tapered slightly, whereby to cause the portions 20 of the spring to be wedged apart temporarily 75 when the trunnion is being inserted in the bracket 12.

It will be appreciated from the foregoing that the spring provides a resiliently yieldable connection in the form of an end-thrust 80 bearing which will prevent end play of the roller between the brackets while permitting the roller to be snapped easily into or out of position.

I claim:

1. In a shade roller mounting, a bracket having a bearing aperture and two offset spring-retaining loops at opposite sides of the aperture, a roller, a trunnion on the roller having a portion journaled in the aperture and a grooved portion beyond the journaling portion, and a U-shaped spring extending across the bracket with the end portions of the spring beneath the loops in the bracket and the intermediate portions of the spring in opposite parts of the groove in the trunnion for resisting endwise movement of the roller.

2. In a shade roller mounting, a bracket having a bearing aperture and two offset spring-retaining loops at opposite sides of the aperture, a roller, a trunnion on the roller having a portion journaled in the aperture and a grooved portion beyond the

journaling portion, a U-shaped spring extending across the bracket with the end portions of the spring beneath the loops in the bracket and the intermediate portions of the 5 spring in opposite parts of the groove in the trunnion for resisting endwise movement of the roller, and a cap on the bracket having

a rim positioned adjacent the extremities of the spring for preventing the spring from working out from beneath the loops. 10

In testimony whereof I have hereunto subscribed my name.

CHARLES P. FREESTATE.
